ATTACHMENT FOR SEWING MACHINES

Samuel H. Boyer, Belmont, N. C., assignor of one-half to J. Mack Hatch, Charlotte, N. C.

Application February 25, 1941, Serial No. 380,529

6 Claims. (Cl. 112—252)

The present invention pertains to sewing machines, and it comprises novel mechanism for feeding the fabric through the machine, and for cutting chains of sewing stitches between the pieces of fabric sewn.

In the practical application of the invention it has been embodied in a sewing machine of the type employed for seaming hosiery, which enables the practice of a novel and advantageous method of seaming hosiery.

In the practice of producing stockings, especially of the full fashioned type, the stockings are knitted as flat fabric blanks, which are folded with side edges juxtaposed, and the edges are sewed together with an overseam to form the stocking tubular. The most common present day overseaming stocking seaming machine is of the cup feed type, and the invention is shown as applied to cup feed sewing machines. However, certain features of the invention are applicable to other types of sewing machines.

Under common prior art practice of seaming stockings, the stocking blanks are fed to the stitch forming mechanism between a pair of oppositely disposed cups, as feed rollers. The cups are driven to rotate at a predetermined speed relative to the speed of operation of the stitch-forming mechanism. By this means the stitches are spaced apart predetermined distances in the fabric. As the stitched fabric leaves the stitch-forming mechanism it is delivered out of engagement with the feed rollers, while the completed stitches nearest the stitch-forming mechanism continues to be subjected to thread tensions applied to the sewing threads. This creates a tendency of the seam to pucker as it leaves the stitch-forming mechanism, and frequently results in an uneven seam being produced with varying degrees of resiliency along its length.

Under prior art practice of stocking seaming, the machine operator grasps the seamed portion of the stocking with the left hand and forcibly draws it away from the stitch-forming mechanism, thus applying a take-up tension to the fabric manually. Obviously, this method is not entirely satisfactory, and results in stocking seams being puckered in places, and uneven.

The present invention comprises a fabric take-up mechanism in a sewing machine, and more particularly, in a cup feed type of overseaming machine. In the practical embodiment of the invention it comprises an auxiliary fabric transmitting roller in yielding engagement with one of the feed cups, and driven thereby. The auxiliary roller is positioned at a point immediately

beyond the feed point of the feeding cups, so located that, as the seam is formed, the stocking passes between the auxiliary feed roller and its coacting feed cup by the natural action of the operator moving her left hand to withdraw the stocking from the stitch-forming mechanism. Thus, the take-up tension is applied to the stocking mechanically, and the operator only handles the stocking to guide it through the machine, and to cut the length of chain stitches intermediate the successive stocking blanks.

The invention comprises a novel chain cutter. Under prior art practice the chain cutter is located below the rearmost feed cup. When the seam of a stocking is completed, the operator continues to operate the machine to produce about five inches of chain stitches. She must then twist her body to the left, and look around the feed cups, in order to apply the length of chain stitches to the cutter. She then sets the seamed stocking beside her in the batch of completed work, prepares the machine to begin the seaming of the next stocking and guides the next stocking blank to the machine. The chain of stitches extending from each end of the completed seam are trimmed to their desired length by a subsequent operation.

Under the practice of the present invention the chain stitch cutter is disposed above the level of the nearest feed cup, in clear view of the operator. It is of less complex construction than the prior art cutter, is more readily removed from the machine for sharpening, and is constructed in a manner to be more easily sharpened.

In the preferred practice of the invention, the novel cutter is positioned above the path of the seamed stockings as they pass beyond the stitch-forming mechanism, and under the auxiliary fabric take-up roller. The cutter is spaced away from the auxiliary roller a predetermined distance, determined by the lengths of chain stitches desired to extend from each end of the seam. Thus, when the operator cuts the chain, there is the desired length of chain stitches extending from the trailing end of the seam of the seamed stocking, and from the leading end of the seam of the succeeding stocking. No subsequent trimming operation is necessary.

The novel method of seaming successive stockings comprises the steps of completing the seam of a leading stocking; then producing a length of chain stitches which is much shorter than under prior practice, and only long enough to comprise the desired lengths of chain stitches extending

from both the leading and trailing ends of a seam in a stocking; then beginning the seam of the next succeeding stocking; and then severing the chain of stitches between stocking blanks midway of its length. The operator guides the seamed stocking through the auxiliary take-up roller with her left hand; then begins the next succeeding stocking into the feed rollers and operates the machine to form seam stitches until the leading end of the succeeding blank passes between the auxiliary roller and its coacting feed roller. She now cuts the intermediate chain of stitches. The cutter is so located that a simple motion of the left hand, which includes the natural motion to deposit the seamed stocking in the batch of completed work, operates to cut the chain. With the completely seamed stocking in her left hand, the operator swings her hand upwardly and forwardly towards her body, placing the stocking beside her where the batch of completed work is positioned.

The invention and its several advantages will be better understood from the showing of the accompanying drawing, in which—

Figure 1 shows an elevation of the machine, with those details which are unimportant for understanding the present invention omitted, the view being taken from the left of the machine, and illustrating the novel mechanism of the present invention;

Figure 2 is a plan view of the fabric transmitting mechanism and its relationship to the stitch-forming mechanism;

Figure 3 is an elevation, partly in section, taken on line 3—3 of Figure 2;

Figure 4 is a perspective view of parts comprising the novel chain cutting mechanism of the present invention; and

Figure 5 is a cross-sectional elevation showing the manner in which the fabric take-up roller and the cutter are mounted.

The drawing shows those portions of a sewing machine to which the invention pertains. The sewing machine may be of any suitable construction. The invention has been practiced in the art of seaming full fashioned hosiery, and, accordingly, the drawing shows an overseaming machine, which is a type commonly employed for seaming hosiery. This machine comprises a pair of feeding discs, 11 and 12, front and rear respectively, Figures 1 and 2, which are driven in opposite directions. The discs 11 and 12 are provided with respective rims 14 and 15, which render the discs cup-shaped. For that reason these machines are commonly termed cup feed machines.

The surfaces of the rims 14 and 15 are serrated, as shown, to enable them to grip and transmit the fabric between them. The cups 11 and 12 are mounted fixed to the respective shafts 16 and 17, which are rotated in opposite directions by driving means contained in the housing 18, which also encloses the main drive shaft, and mechanism to operate the stitch forming mechanism in timed relationship with the feed of fabric thereto by the feed cups 11 and 12. This portion of the machine is well understood, and requires no further explanation herein. The shafts 16 and 17 are enclosed in the respective shaft housings 19 and 20.

The stitch forming mechanism includes the needle 21, which is reciprocated horizontally in a path immediately above the upper edges of the rims 14 and 15, where the rims engage each other at the feed point 22. Supported by the bracket 24, comprising the lower extremity of the shaft housing 19, is the needle guide block 23, which guides the needle in its passage over the front

feed cup 11. The hereinbefore described structure is old and well known in the art, and constitutes so much of the prior art as pertains to the present invention.

5 The device of the present invention comprises means to prevent puckering of the seam as it leaves the stitch-forming mechanism. Mounted on the needle guide block 23, Figure 2, to pivot on the pin 26, is the arm 27. At the end of 10 the arm 27, mounted to pivot on the pin 28, is the auxiliary fabric transmitting roller 29, the arm 27 being deflected downwardly at 30, Figures 4 and 5, to position the roller 29 in face to face engagement with the rim 14 of the feed cup 11. The 15 roller 29 is held in yielding engagement with the face of the rim 14 by means of the torsional coil spring 32, which is coiled around the pivot pin 26 of the arm 27. See Figure 1. The force with which the roller 29 engages the cup surface 14 is 20 adjustable by means of the plurality of holes 33, in any of which, one end of the spring 32 can be projected selectively for different spring tensions. The face of the roller 29 is serrated, as shown, for gripping engagement with the surface 14 of 25 the disc 11.

The roller 29 engages the rim 14 at a point beyond the stitch forming position at 22. As is well understood in the art of seaming full fashioned hosiery, each stocking blank is folded with 30 its side edges juxtaposed, and at one end thereof the juxtaposed edges are guided to a position between the pair of feed cups 11 and 12, with the help of suitable guiding means which form no part of the present invention. The stitch-forming mechanism is power driven to operate to 35 form stitches, and the cups 11 and 12 are simultaneously driven to rotate in timed relationship with the stitch-forming operation, to transmit a predetermined length of the edges of the fabric blank through the feed point 22 during the 40 formation of each stitch.

Under common prior art practice the operator guides the stocking blank to the stitch-forming point 22 by grasping the unseamed portion of the 45 stocking with the right hand. As the seamed portion of the stocking emerges from the feed rollers 11 and 12 beyond the stitch-forming needle 21 located at the feed point 22, the newly formed 50 seam stitches remain subjected to the tension of the sewing threads, and this tension has a tendency to pull the threads of formed stitches, and to pucker the seam. This is obviated to a degree, under prior art practice, by the operator grasping the seamed portion of the stocking with 55 the left hand and applying a manual take-up tension to the seam and the stocking, and drawing the stocking away from the feed point 22. The operator sits in a position to the right of Figure 2, facing the feed roller 11, with the feed 60 roller 12 behind it and slightly to the right. She grasps the unseamed portion of the stocking with the right hand, and the seamed portion thereof with the left hand. With the left hand she draws the stocking blank to the left, and, 65 naturally, as a result of her position, she draws the blank somewhat towards her body and in engagement with the face 14 of roller 11. Under this circumstance the stocking blank will continue in contact with the face 14 of the front feed 70 roller 11 after it leaves the feed point at 22, until it progresses to a position between the auxiliary roller 29 and the feed roller 11. The blank is, thus, advanced by the rollers 11 and 29 under a uniform mechanically applied take-up tension.

75 Novel means are provided to cut the chain of

stitches between successive stocking blanks, and this comprises the cutter 34, attached to the end of the arm 27 by means of the pin 35. The cutter 34 lies flat on the top surface of arm 27. It projects forwardly, away from the attaching pin 35 along the arm 27, and terminates with the end projection 36, which overhangs the edge of the arm 27 and engages its deflection 38, to hold the cutter in predetermined proper position relative to the roller 29. The cutter is provided with the rearwardly directed notch 37, positioned to receive the chain of stitches between stocking blanks when the leading blank is swung upwardly and forwardly, towards the body of the operator. The notch 37 is ground beveled, as indicated at 38, to provide a sharp cutting edge, which terminates at the apex 39 of the notch. At 39 the cutting edge is rounded, as shown, to provide a continuous cutting edge instead of a wedgelike notch which would operate to tear, rather than to cut, the chain. The notch 37 can be beveled on top, as shown, or on the bottom, or on both sides. However, the latter structure is not preferred because one surface of the cutting edge should be flat with the surface of the cutter. By this means the cutter can be readily sharpened by simply sliding it across the surface of a whet stone.

The chain stitch cutter 34 of the present invention replaces the cutter conventionally present in the prior art, which prior art cutter is attached to the machine housing, and projects forward therefrom into position under the rear feed roller 12. Under the prior art practice, the operator draws the stocking away from the feed point 22 and the stitch-forming mechanism, applying the take-up tension to the blank manually, until the seam is completed. She thereupon continues to operate the machine to produce a length of chain stitches, about five inches thereof being necessary to reach the prior art cutter. She then reaches around the left side of the machine to place the chain into the cutter, and she draws the seamed blank to the left to cut the chain. It is necessary for her to lean to the left to see what she is doing. The chains of stitches extending from each end of the seam are trimmed to the desired length in a subsequent operation.

With the structure of the present invention the operator practices a novel method of seaming successive stocking blanks, which method is less time consuming, and less tiring to the operator, and which method produces a better and less costly seam.

Under the practice of this novel method, the operator guides the leading blank 41 to her left and forward between the feed roller 11 and the auxiliary roller 29, until the seam 42 is completed, when the operator continues to produce a predetermined length 43 of chain stitches which is much shorter than under prior art practice. She thereupon begins to guide a succeeding blank 44 into the feed point at 22, and through the stitch forming operation, drawing on the blank 44 by exerting slight tension on the chain of stitches 43. By this means the leading end of the succeeding stocking blank 44 follows the surface 14 of the roller 11 until it passes under the auxiliary roller 29. The operator now stops the machine only long enough to dispose of the preceding seamed blank 41, and this is done by the simple act of swinging the left hand upwardly and forwardly. This movement places the leading stocking blank into the position illustrated in Figures 2 and 3, with the chain of stitches intermediate the respective leading and succeed-

ing blanks, 41 and 44, disposed in the notch 37 of the cutter. The operator continues the movement of her left hand to place the seamed blank beside her in the batch of finished work, and this movement cuts the chain of stitches midway between the trailing end of seam 42 and the leading end of seam 45. The operation of the cutter 34 is in clear view of the operator, and the operation is the natural movement by the operator to deposit the seamed blank with the batch of completed work.

It will be noted that, after the operator has placed the seamed stocking 41 aside, the succeeding stocking 44 is in ready position to be grasped by the left hand to be guided through the machine. The succeeding stocking blank is already started through the machine, and is under take-up action of the auxiliary roller 29.

The length 43 of chain stitches between succeeding stocking blanks is easily gaged to be long enough to properly position the chain in the cutter 34 when the leading end of the trailing blank 44 has entered between the feed roller 11 and auxiliary roller 29, in the position illustrated in Figures 2 and 3. The cutter is so located relative to the roller 29 that the desired length of chain stitches is left extending away from the trailing end of the seam 42 of the leading stocking blank 41, and also from the leading end of the seam 45 of the succeeding stocking blank 44.

The structure shown in the drawing presents one practical embodiment of the invention which, however, is susceptible of a number of modifications within the scope of the invention. Accordingly, applicant is not to be limited by the structure shown, but the scope of the invention is determined by the accompanying claims.

What is claimed is:

1. A stocking seaming machine comprising a mechanism operable to form the seam stitches, and mechanism to transmit the stocking blanks through the machine, the transmitting mechanism including a pair of feed rollers driven in timed relationship with the stitch-forming mechanism in opposite engagement at the stitch-forming mechanism to present a blank thereto at the desired predetermined rate, an arm pivoted above one feed roller, an auxiliary transmission roller rotatably carried by said arm beyond the periphery of the said roller, a spring urging the arm towards the feed roller to hold the auxiliary roller in engagement with the feed roller to be driven thereby, the auxiliary roller being positioned at a point beyond the stitch-forming mechanism to take-up the blank as it is seamed in timed relationship with the formation of the seam, and a cutter carried by the arm beyond the auxiliary roller.

2. A stocking seaming machine comprising a mechanism operable to form the seam stitches, mechanism to transmit the stocking blanks through the machine, and a cutter to separate seamed blanks, the transmitting mechanism including a pair of feed rollers driven in timed relationship with the stitch-forming mechanism in opposite engagement at the stitch-forming mechanism to present a blank thereto at the desired predetermined rate, an auxiliary transmission roller in engagement with a feed roller to be driven thereby, and positioned at a point beyond the stitch-forming mechanism to take-up the blank as it is seamed in timed relationship with the formation of the seam, the cutter being positioned above the path of the stocking blank in proximity to the auxiliary roller.

3. In combination with a stocking seaming machine including rotatably mounted feed rollers and stitch-forming means adjacent contacting portions of the rollers, an arm mounted over one roller, an auxiliary roller rotatably carried by said arm and frictionally driven by contact with the peripheral edge of one of the feed rollers and cooperating therewith for drawing a seamed blank away from the stitching mechanism, and a cutter carried by said arm.

4. In combination with a stocking seaming machine including stitching means and feed rollers having contacting portions adjacent the stitching means, a mounting above one roller, an arm pivoted to said mounting and extending beyond the periphery of said roller, an auxiliary roller rotatably carried by said arm opposite the peripheral edge face of the roller, a spring urging the arm in a direction to yieldably hold the auxiliary roller in engagement with the peripheral edge face of the said roller in spaced relation to the stitching means circumferentially of the roller, the auxiliary roller being driven from the roller engaged thereby and cooperating therewith for drawing a seamed portion of a blank outwardly from the stitching means for a portion of the periphery of the said roller, and a cutter carried by said arm.

5. In combination with a stocking seaming machine including stitching means and rollers for delivering a blank to the stitching means, an arm pivotally mounted over one feed roller and yieldably held against swinging movement away from the said roller, an auxiliary roller, a pin carried by said arm and rotatably mounting the auxiliary roller in position for contacting engagement with the said feed roller, the auxiliary roller being rotated by the said feed roller and cooperating therewith for drawing a seamed portion of a blank away from the stitching means, and a cutter having a shank secured against said arm and a sharpened bill projecting from the arm.

6. In a combination with a stocking seaming machine including rotatably mounted feed rollers and stitch-forming means associated therewith, a mounting above one roller, an arm pivoted to said mounting and projecting beyond the periphery of the said roller, an auxiliary roller carried on the free end of said arm, a spring urging the arm toward the one feed roller to yieldingly retain said auxiliary roller against the last mentioned feed roller, and a cutter carried by the projecting free end portion of said arm above the plane of and in proximity to said feed rollers.

SAMUEL H. BOYER.
